STUFFED ANIMAL FIGURE

Christine H. Oswald, Falls Church, Va.

Application May 25, 1955, Serial No. 36,207

Term of patent 14 years

(Cl. D34—2)

Figure 1 is a perspective front view of a stuffed animal figure, with the limbs extended, showing my new design.

I claim:

The ornamental design for a stuffed animal figure, substantially as shown and described.
